UNITED STATES PATENT OFFICE.

HOWARD HARSH, OF OSAKIS, MINNESOTA.

REVERSIBLE RAILROAD-TIE.

1,242,184.

Specification of Letters Patent.

Patented Oct. 9, 1917.

Application filed February 17, 1917. Serial No. 149,351.

To all whom it may concern:

Be it known that I, HOWARD HARSH, a citizen of the United States, residing at Osa-
kis, in the county of Douglas and State of
5 Minnesota, have invented certain new and
useful Improvements in Reversible Rail-
road-Ties; and I do hereby declare the fol-
lowing to be a full, clear, and exact descrip-
tion of the invention, such as will enable
10 others skilled in the art to which it appertains
to make and use the same.

This invention relates to railroad ties and
more particularly to a reversible cement tie.

The principal object of the invention is
15 to provide a railroad tie of this character
which consists of a pair of tie sections that
are secured together, cushioning means be-
ing positioned between the sections so as to
allow the tie sections a certain amount of
20 elasticity and which will function the same
as the wooden tie.

A further object of the invention is to
provide each tie section with removable rail-
holding devices whereby when the tie sec-
25 tions have been reversed bottom for top, the
rail-holding devices may be again secured
in position to clamp the rails in position.

A still further object of the invention is
30 to provide each tie section with rail-securing
devices which may be adjusted to accom-
modate rail flanges of various widths, and
which may be adjusted vertically in these
adjusted positions to permit of the rails be-
35 ing shimmed up.

With these and other objects in view as
will appear as the description proceeds, the
invention comprises various novel features
of construction, combination and arrange-
40 ment of parts, as will be more fully de-
scribed hereinafter and set forth with par-
ticularity in the appended claims.

Referring to the drawings,

Figure 1 is a side elevation of my novel
construction of reversible railroad tie.

45 Fig. 2 is a vertical transverse sectional
view taken on the line 2—2 of Fig. 1.

Fig. 3 is a vertical sectional view taken
on the line 3—3 of Fig. 2.

Fig. 4 is a fragmentary vertical sectional
50 view taken through the adjacent ends of the
tie sections.

Fig. 5 is a vertical sectional view taken
on the line 5—5 of Fig. 2.

Fig. 6 is a vertical sectional view through
55 one of the spike holder casings.

Fig. 7 is a fragmentary sectional plan
view taken on the line 7—7 of Fig. 3, and

Fig. 8 is a similar view showing the spike
holder adjusted to accommodate a rail flange
of larger width. 60

Similar characters of reference are used
to denote like parts throughout the accom-
panying drawings and the following de-
scription.

Referring more particularly to the draw-
ings, the reference numeral 1 indicates a
pair of tie sections comprising my novel
construction of reversible railroad tie, and
while I prefer to have this tie constructed
of cement, it is to be understood that it 70
may be constructed of any other material
found desirable and best suited for the pur-
pose. These tie sections are adapted to be
secured together through the medium of
spaced tie rods 2 that extend entirely 75
through each of said sections and have their
outer ends provided with retaining nuts 3
and lock washers 4 so as to securely hold
said sections together. These tie rods pass
through pipe casings 5 arranged within each 80
tie section which are provided at their op-
posite ends with flanges 6, these pipe casings
being roughened on their outer surfaces so
as to prevent them from slipping, and if
desired may be of non-circular contour in 85
cross section.

The adjacent ends of the tie sections are
each provided with a pair of metallic sock-
ets 7 that are arranged one above the other
and designed to alternately receive a cush-
ioning spring 8, said sockets being each pro-
90 vided with circumferential flanges 9 seated
within the opposed faces of the tie sections.

The cushioning spring is designed to be
normally arranged in the lower pair of
95 sockets and positioned between the adjacent
ends of the tie sections is a wedge member
10. This wedge 10 is arranged at the top
portion of the tie sections and is designed
to be securely held in place by the upper 100
pair of tie rods passing through its oppo-
site ends. When the wedge is arranged in
this position it will serve to hold and main-
tain the tie sections 1 in substantially rigid
105 longitudinal alignment and prevent sagging
of their inner adjacent ends and yet permit
of a slight vertical vibratory movement of
them due to the stress and the concussions
imparted thereto by the passage of heavy
trains thereover. By this construction and 110

the cushion spring, it will be obvious that the tie sections will possess a certain amount of elasticity or that equivalent to that of the usual construction of wooden ties.

5 When the tie is reversed bottom for top, the cushioning spring and the wedge are also reversed so as to occupy the same relative position as shown.

Each tie section is provided adjacent its outer ends with a pair of elongated spike-holding devices 11, each of which, as shown in Figs. 7 and 8, is oblong in cross section and has one of its longitudinal sides open so as to accommodate a latch member 12 15 that is pivotally mounted at its lower end, as indicated by the numeral 13, the upper end being provided with a set-screw 14.

Each of these latch members is further provided intermediate its ends with a shoulder 15 disposed on its outer side and which is designed to lockingly engage within the recess 16 formed intermediate the ends of a casing 17, by off-setting or bulging the walls of the casing outwardly. As shown, this 25 recess 16 extends around three sides of the casing, whereby the spike holders may be adjusted around and arranged in three different positions within the casing.

When it is desired to secure the rails 30 18 in position upon the tie, the spike holders are inserted within the respective casings and the shoulders 15 engage within the recesses thereof, whereby the usual spikes 19 may be driven down within the spike 35 holders between the latch members 12 and the inner wall of the spike holder until the head of each spike rests firmly upon the base flange of each rail. As soon as each spike has been driven home, the set-screws 14 40 may be turned up so as to lock the spikes in position and against accidental displacement or from working loose.

If it is desired to adjust the spike holders to accommodate a rail having a base 45 flange of a larger width, it is simply necessary to arrange the spike holders in the position shown in Fig. 8, from which it will be obvious that by reason of the spike holder being oblong and the casing square, 50 that the distance from the center of the rail to the shank of the spike will have been slightly increased or a sufficient amount to accommodate this base flange of larger width. By providing the casing 17 with a 55 recess extending around three sides thereof, the spike holder may be adjusted horizontally in either direction and again positioned within the casing and in locking engagement therewith.

60 It is also to be noted that by the particular construction of spike holder shown, the rails may be shimmed up and the spikes ad-

justed vertically and subsequently locked in position by the set-screws 14 to hold the rail in adjusted position.

It will also be noted that since the recesses 16 are formed intermediate the ends of the casings 17, that when the tie has been reversed top for bottom, the spike holders can also be reversed and inserted from the 70 opposite ends of the casings 16.

What I claim as new is:—

1. A reversible tie comprising a pair of tie sections, pipe casings arranged through each tie section, tie rods disposed through 75 said pipe casings and serving to connect said tie sections together, cushioning means positioned between said sections, and means for securing a pair of rails in position upon the tie.

2. A reversible railroad tie comprising a pair of tie sections, means for securing said sections together, a wedge arranged between the meeting ends of said sections and positioned adjacent the top portion thereof, 85 cushioning means arranged between the meeting ends of said sections and positioned adjacent the bottom portions thereof, and means for securing a pair of rails in position upon said tie.

3. A reversible railroad tie comprising a pair of tie sections, means for connecting said sections together, a wedge removably positioned between the tie sections, cushioning means removably positioned between the 95 meeting ends of the tie sections, and rail-securing devices removably positioned within each tie section, whereby the tie sections may be reversed top for bottom.

4. A reversible railroad tie comprising a 100 pair of tie sections having a pair of alining sockets in their opposed ends adjacent the bottom portions thereof, spacing means arranged between the meeting ends of said 105 sections and positioned adjacent the top thereof, a cushion spring arranged in said alining sockets, and means for securing said tie sections together.

5. A reversible railroad tie comprising a pair of tie sections having a pair of alining 110 sockets adjacent the top and bottom portions of said sections, removable spacing means arranged between the meeting ends and adjacent the top of said sections, a cushion spring removably arranged in the 115 lower pair of alining sockets, and means for securing said tie sections together.

In testimony whereof I have signed my name to this specification in the presence of two subscribing witnesses.

HOWARD HARSH.
